SCREEN GRID STRUCTURE FOR ELECTRON DISCHARGE TUBES

Johan Lodewijk Hendrik Jonker and Adrianus Johannes Wilhelmus Marie van Overbeek, Eindhoven, Netherlands, assignors to Hartford National Bank and Trust Company, Hartford, Conn., as trustee

Application July 15, 1946, Serial No. 683,591
In the Netherlands February 16, 1943

Section 1, Public Law 690, August 8, 1946
Patent expires February 16, 1963

1 Claim. (Cl. 313—300)

1

The present invention relates to an electric discharge tube which comprises at least two control grids and wherein a positive screen electrode is arranged between these grids, and, more particularly, to the construction of this screen electrode.

The electron current is checked by a control grid to a larger or smaller proportion according to the potential of this grid. The checked electrons may return in this case and may give rise to negative space charges in the neighborhood of the cathode or of a preceding grid, which may be undesirable. This phenomenon is particularly inconvenient in the case of tubes with two or more control grids, as in frequency changers, for example, hexodes, heptodes, octodes and the like.

In tubes of this type wherein generally a screen grid is arranged between the two control grids, this screen grid may be wound very tightly in order to intercept the electrons which return from the second control grid. In this case, however, a large proportion of the electron current is directly intercepted by this screen grid, which causes a decrease in the slope of the characteristic curve of the tube.

It is furthermore known to give the second control grid such a shape or position that the returning electrons are deflected in a determined manner and reach one or more suppressor electrodes specially provided for this purpose so that they cannot return to the neighborhood of the first control grid. This method has the drawback that to direct the said electrons along another path the returning electrons need a certain space, due to which there are produced undesired space charges which impede the passage of a larger electron current, which results in a decrease in the slope of the characteristic curve of the tube. Moreover, in this case the electron current is frequently directed to the second control grid at a certain angle in order to impart to the electrons which return a lateral velocity component in the direction of the said suppressor electrodes so that the whole of the electron current is only allowed to pass when the control grid has a positive voltage, which causes inconveniences due to the fact that the grid begins to carry current. This inconvenience is particularly prevalent when use is made of automatic volume control.

2

According to the invention, the above-mentioned drawbacks are considerably reduced if in an electric discharge tube which is equipped with an electrode system comprising at least two control grids and wherein a positive screen electrode is arranged between these grids, the screen electrode consists of a plurality of plate-shaped parts whose faces are parallel or substantially parallel to the principal direction of the electron paths, for it has been found that even if the electron current arrives on the face of a control grid at a right angle, the returning electrons acquire a component of lateral movement. This is caused by the unequal potential distribution in the face of this control grid due to the presence of the grid wires. It is thus possible to intercept the returning electrons with the aid of the screen electrode according to the invention without any risk of an appreciable proportion of the principal current being taken away by this screen electrode. Since the returning electrons are required to travel very short distances in order to reach the plate-shaped portions of the screen electrode, the space charges are small so that the slope of the characteristic curve may be increased. Since there is no objection to electrons arriving at right angles to the surface of the particular control grid because the returning electrons acquire a lateral component of velocity in any case, an increased slope can likewise be obtained by permitting electrons to reach the second control grid at right angles so that substantially the entire electron current will pass the latter grid at a grid voltage of 0 volt with respect to the cathode.

The plate-shaped parts of the screen electrode may be provided in different ways. Care must be taken, however, to ensure that the narrow sides of these portions are always turned towards the cathode so that as few electrons of the principal current as possible are intercepted. In this case the plate-shaped parts may be constituted by a plurality of flat rings arranged at some distance above one another. It is also possible, however, to build up the screen electrode from a plurality of strips which are arranged according to the direction of the length of the cathode; here again the narrow sides must be turned towards the cathode. It is also possible to arrange such strips at an acute angle with respect to the longitudinal

20202020

3

axis of the cathode. It is furthermore possible to build up a honeycomb structure with the aid of such strips.

The electrode configuration according to the invention is utilized with the screen electrode arranged on the cathode side of the input control grid. In frequency changers wherein the second control grid is generally utilized as the input control grid, this screen electrode according to the invention may consequently be arranged between the two control grids.

The invention will be explained more fully with reference to the accompanying drawing wherein

Fig. 1 represents diagrammatically the paths of the electrons.

Fig. 2 elucidates the effect of an electrode according to the invention.

Fig. 3 is a cross-sectional view of an electric discharge tube embodying an electrode in accordance with another embodiment of the invention.

Fig. 4 is a cross-sectional view of an electric discharge tube embodying an electrode in accordance with a further embodiment of the invention.

In Fig. 1 the electron paths of the principal current and the paths along which the electrons are repelled by a control grid 3 are denoted by 1 and 2 respectively. The repelled electrons generally acquire a lateral speed component due to the presence of the grid wires 3.

Fig. 2 represents a cathode 4 from which the electrons pass through a grid 5 to a control grid 6. According to the invention plate-shaped parts 7 are arranged parallel to the electron paths 1. After having covered a short distance the electrons repelled according to the paths 2 are intercepted by the screen parts 7 which may have the shape of flat rings. The rings 7 are arranged at a short distance above one another and are united to form an electrode.

One form of construction has been described above in detail. However, it is evident that, as has been mentioned hereinbefore, the flat parts of the electrode according to the invention may also be provided in other ways. The discharge

tube shown in Fig. 3 comprises within an envelope 10 an electrode assembly consisting of a cathode 4, a first grid 5, a second grid 6, an anode 8 and interposed between the grids 5 and 6 a screen electrode 7a in the form of a plurality of strips arranged parallel to the longitudinal axis of the cathode. In the arrangement of Fig. 4 the screen electrode shown as 7b is in the form of a honeycomb; the remaining parts of the tube being the same as previously described.

What we claim is:

An electric discharge tube comprising an envelope, a set of concentric electrodes within said envelope comprising an anode, a cathode, two electron permeable control grids interposed between said anode and said cathode, and a screen grid interposed between said control grids and consisting of a plurality of thin substantially planar strips having spacings therebetween, the longest dimension of each portion being greater than the said spacing between adjacent portions, said strips being disposed substantially coincident with radial planes through the axis of said cathode.
